INVENTOR

James Leslie Wilson
BY *Wm. C.*
ATTORNEYS

UNITED STATES PATENT OFFICE.

JAMES LESLIE WILSON, OF DAVENPORT, IOWA.

INSULATOR.

Application filed April 6, 1921. Serial No. 458,941.

To all whom it may concern:

Be it known that I, JAMES LESLIE WILSON, a citizen of the United States, and a resident of Davenport, in the county of Scott and State of Iowa, have invented a new and Improved Insulator, of which the following is a full, clear, and exact description.

This invention relates to electrical supporting insulators for current-carrying wires. An object of the invention is to provide an insulator to which the wires or devices to be supported can be very quickly, simply and efficiently attached without the wire or supported device coming in contact with metal or conducting material on the insulator.

Another object resides in the provision of means whereby in its passage through the insulator the wire or device can swing or have a curved passage without being subject to wear or friction.

A further object resides in the provision of means whereby the wire is held firmly in place by a cover portion which can be very quickly and easily applied to and removed from the body portion of the insulator.

A still further object resides in the particular construction and arrangement of parts which are hereinafter described and claimed and shown in the accompanying drawings.

The invention is illustrated in the drawings, of which—

Figure 1 is a view of the insulator with the central portion in sections;

Figure 2 is a side elevation thereof;

Figure 3 is a top plan view of the body portion of the insulator with the wire or conductor shown in place; and

Figure 4 is an inverted plan view of the cover portion of the insulator.

The preferred embodiment of my invention, as shown in the drawings, comprises an insulator having a body portion 1 and a cover or top portion 2 which is adapted to be applied to the body portion 1. The cover and body portions are adapted to meet in a flat contacting surface such as 3. On the upper surface of the body portion 1 are

provided a pair of spaced projecting ribs 4 and 5 which project upwardly from the surface of the body portion 1 and extend across this surface between opposite edges. The

outer edges 6 of the ribs are straight, whereas the inner adjacent edges 7 are symmetrically curved as shown in Fig. 3. These ribs form between them a recess in which a wire or conductor such as 8 is adapted to lie. By having the adjacent edges or surfaces 9 curved, it will be observed that the wire 8 can swing in the recess formed between the ribs 4 and 5 or pass therethrough in a curved manner without meeting any sharp edges, whereby it is not subjected to wear or friction. The lower surface or face 65 of the cover portion 2 is provided with a recess 9 of a depth equal to the height of the ribs 4 and 5, and a width substantially equal to the width between the outer edges 6 of the ribs 4 and 5. This recess is provided 70 with lateral walls 10 which are adapted to lie closely adjacent the edges or surfaces 6 of the ribs when the cover is placed on top of the body portion 1.

In a line at right angles to the line of extension of the recess 9, through the cover portion 2 and on opposite sides thereof, are disposed a pair of projecting lugs 11 to which suitable latch members 12 are pivoted. These latch members 12 are made of 75 wire bent over in the form shown to engage with lugs 11 and at the other end provided with an under-turned loop portion 13 which is adapted to engage under the lower edge 80 of a shoulder 14 on the body portion. This shoulder 14 is in the form of an outwardly 85 projecting flange portion extending circumferentially completely around the body portion.

In the application of the device, the cover portion is supposed to be removed from the body portion; whereupon the conductor or wire 8 is placed in position. The cover portion is then placed on the body portion with the recess 9 disposed over and embracing the ribs 4 and 5 and, therefore, confining the wire in the grooves between the ribs 4 and 5. The latch members 12 are caught under the edges of the flange or shoulder 14, and by reason of the resiliency of each wire latch member 12, the cover is held 95 firmly on to the body portion.

What I claim is:

An insulator, comprising a body having at the upper end an annular shoulder and provided on its upper face with spaced ribs 105 of a height a little greater than the diam-

2

eter of the wire to be held therebetween, straight walls lying close to the straight
said ribs extending entirely across the body outer edges of the ribs, and latch members
and having curved inner edges and straight pivoted to opposite sides of the cover and 10
outer edges, a cover having in its lower face engaging the shoulder of the body to lock
a recess of a depth equal to the height of the cover on the body with their faces di-
the ribs, said recess extending entirely rectly in contact with each other.
across the face of the cover and having JAMES LESLIE WILSON.
